UNITED STATES PATENT OFFICE

2,201,136

FULL FASHIONED KNITTING MACHINE

Kenneth Howie, Norristown, Pa., assignor to
 Wildman Mfg. Co., Norristown, Pa., a corpora-
 tion of Pennsylvania

Application July 16, 1937, Serial No. 154,104

4 Claims. (Cl. 66—89)

This invention relates to fashioning knitting machines and particularly to the mechanism for transferring stitches from needle to needle.

The invention is applicable to full fashioned or flat knit stocking machines of the so-called Wildman type, one example of which is shown in Letters Patent of the United States to Howie and Krieble No. 1,982,991, dated December 4, 1934, known on the market as the Wildman single-unit 10 single-head machine of the TW type, though it will be understood that the invention may be practiced in connection with other types of machines.

The present machine is adapted to make a 15 complete stocking blank, the leg and foot being produced in one continuous operation, though the invention is not limited in this respect.

In the accompanying drawings

Figure 1 is a front view of the needle bar, the 20 narrowing points and associated mechanism.

Fig. 2 is a front elevation of a narrowing block.

Fig. 3 is an end elevation of the narrowing block shown in Fig. 2.

Figs. 4 and 5 are rear elevations of the narrowing blocks in operating position.

Fig. 6 is a view of mechanism for giving the front and back screw threaded shafts forward and backward movements for narrowing and widening, the front shaft adjusting the transfer 30 point blocks, and the back shaft adjusting yarn carrier stops.

Figs. 7 and 8 are detail views relating to Fig. 6.

The narrowing mechanism is indicated generally at 184 in Fig. 1. It includes the opposite 35 threads 185, 186 on a front shaft 44b controlled by a gearing 187 as in the said patent to Howie and Krieble, and need not therefore be more particularly described. In the said patent there are shown narrowing or widening blocks which correspond to the blocks 188, 189 shown herein in Fig. 1. The said blocks are internally threaded so as to be operated by the screw threads 185, 186. In addition to what is just referred to in said patent, I have here provided supplemental 40 blocks 190, 191, which are supported upon the said threads 185, 186, but are not themselves internally threaded, so that they are not, by any threaded engagement with the said threads 185, 186, moved thereby.

50 The respective blocks 188, 190 and 189, 191 act as two units during the narrowings at the leg, namely, at the flare and at the calf, and also in the sole narrowings, and they also act as widening instrumentalities in knitting the heel portions. In knitting the toe narrowings however,

I provide for a relative movement of the two parts of each of said units. This is done by the following mechanism.

A bar 192 forming a part of the narrowing organization and extending transversely thereof, is provided at two points near midwidth of the blank with like plates or cam elements 193, one of which is shown in Fig. 5, and the other of which is employed in connection with the other narrowing block unit. Each said plate is adjustably secured by screw and slot construction 194 to the said bar 192. There is provided at each narrowing block unit a lever 195 pivoted at 196 and having an end 197 adapted at the commencement of the toe narrowing to ride under the corresponding plate 193 and elevate its opposite hooked end 198 out of engagement with a lug or projection 199 upon the small block 191. This, therefore, permits the larger block 189 to act independently of the smaller block 191. The same 20 is true at the left hand portion of the toe with respect to the larger block 188 and the smaller block 190.

The construction is such that when the knitting of the toe narrowings is to commence, both the 25 large block and the small block of each unit go down with the narrowing frame together and take stitches from the fabric and transfer them one stitch inward. Then as the narrowing frame rises to its upper position the screw shaft is given 30 a backward movement by a hook substantially like that shown at 46 in the Howie and Krieble patent by which backward movement of the shaft the two large blocks 188 and 189 will be moved outward but will leave the smaller blocks 35 190, 191 undisturbed. In the second course, therefore, upon the descent of all the narrowing blocks, the smaller blocks 190, 191, although they take stitches, do not transfer them, because the said smaller blocks have not received any transverse 40 movement. The larger blocks 188, 189, however, have received a transverse movement from the said threads 185, 186, and therefore transfer stitches one needle laterally inward. In such 45 transferring action, each of the larger blocks is then brought into contact with the smaller blocks and upon the next course each large and corresponding small block go down as a unit and take up all the stitches which are thus laterally transferred one stitch inward. Upon the fourth 50 course the action is the same as upon the second course, and so on in alternate courses throughout the narrowing of the toe.

In the operation of the machine, and supposing that the legs are being knitted; when the leg 55

narrowings are to be formed, the two blocks of each group of points are connected together by the locking lever 195 to move as one body. After the points have taken the stitches from the needles, the screw shaft 184 is turned, moving the transfer points made up of the two groups at each side of the fabric inwardly, and this operation is repeated until the leg narrowings are completed.

10 During the action just described, the screw shaft is operated from a cam on the main shaft through a lever 43g and a band 44e substantially as in the Howie Patent 1,982,991, the movement being communicated from the spring drum 44' operated by the band through pawl and ratchet means 44f, 44g and gearing to the screw shaft. The pawl is controlled by a pivoted shutter or shield a which in turn is controlled through a quadrant a1 carrying an arm with a roller or projection c thereon. This arm has a spring which holds the shield normally in position to allow the pawl which turns the shaft for narrowing to perform its function by engaging its ratchet for the narrowing operation. There is also a reversing pawl 44f' for giving a reverse movement to the screw shaft for widening, said pawl being carried by a spring drum 44x operated in the reverse direction from the drum first mentioned by a second band 44e', this band also being operated 20 from the lever 43g from the cam on the main shaft. The shutter or shield, above mentioned, also controls this reversing pawl, and for this purpose the shutter is operated to shield the pawl first mentioned and to release the reverse pawl. 25 This operation is performed by the roller on the arm of the quadrant contacting an abutment x, which is set in position by a rod d from a cam not shown located on the controller shaft b of the Howie et al. patent above mentioned. When the reverse pawl is thrown into action by the withdrawal of the shield or shutter, the screw shaft 184 is given a reverse movement for widening in order to form the heel, the members of the pairs of blocks at each side of the fabric remaining connected by the lever 195. When the narrowing points are being moved inwardly to position them for toe narrowing the locking lever 195 comes into contact with the plate 193 and the operation set out above takes place, that is, the said lever is moved to disconnect the main and the supplemental blocks, and the toe narrowings are then introduced.

In performing the toe narrowings for a regular stocking, i. e. one without warp threads, the 55 upward movement of the narrowing frame causes the retrograde pawl 46 (Howie et al. Patent 1,982,991) to retract the large narrowing block away from its small companion block one needle space. In transferring the stitches for narrowing the large block is moved two needle spaces inwardly, thus pushing the smaller block one needle space. When the narrowing frame again rises the large block is moved outwardly one needle space and then inwardly two needle 60 spaces again pushing the small block one needle space and these actions are repeated on every complete operation of the narrowing frame during the toe narrowing operation. The stitches taken by the transfer points of the large block 65 are transferred two needles, whereas the stitches taken on the points of the smaller block are transferred one needle.

The back screw shaft is controlled by pawl and ratchet and shutter means substantially like 70 that described for the front screw shaft.

Reverting to the operation of pawl or hook 46, this may be controlled from the controller shaft b of the Howie and Krieble patent by a suitable cam on said shaft and a connection leading therefrom to said hook. The means illustrated in the Howie and Krieble patent, however, consists of a shaft 46e Fig. 1 and parts associated therewith, and means similar to this last mentioned mechanism may be used in the present machine.

10 Reverting to the locking levers 195 for automatically connecting the large and small transfer point carrier blocks together it will be understood that these may be operated to effect this automatic locking in any suitable way such as 15 in the Wildman marketed form of machine. A spring stresses the locking lever to re-engage the shoulder or projection on the small block, and this spring may be coiled about the pivot of 20 the lever.

The relation between the parts is such that when the lever 195 is down at that end 198 which is to engage the small block, said block will be closed edge to edge against the larger block. When the lever at its end 198 is raised by 25 its opposite end 197 riding under the rail 193 on the fixed frame, it will allow independent movement of the large block in relation to the small block because there will be space between the side of the end 198 of the lever and the side 30 of the shoulder on the small block. The engaging end 198 of said lever, however, will not lift above the level of the shoulder 199 on the small block, so that when the large block is moved to starting position i. e. towards the right in 35 Fig. 5a it will carry the small block with it, though said small block will be spaced apart slightly from the large block. When the large block is moved to position for narrowing it will close against the small block and the locking lever 195 will assume its locking position under the action of its spring as in Fig. 4, so that the two groups of transfer points will then move 40 as one body for performing either narrowing of 45 the leg or widening of the heel.

While the invention is applicable to full fashioned machines of the Wildman type, one example of which is noted above, it will be understood that it is not limited in its use to any 50 particular machine, nor to the character of the knit fabric, the scope of the invention being defined by the appended claims.

I claim:

1. Narrowing mechanism for flat knitting machines comprising at each side of the fabric an inner and an outer comb of fashioning points, and means for locking together the combs at each side whereby they will have conjoint motion, including a lever having a pivotal connection with one of the combs and having a portion for engaging with a part of the other comb to prevent separation of the combs, said lever being pivotable to a position which will permit separation of the combs.

2. Narrowing mechanism for flat knitting machines comprising at each side of the fabric an inner and an outer comb of fashioning points, and means for locking together the combs at each side whereby they will have conjoint motion, including a hook-shaped lever having a pivotal connection with one of the combs, and, on the other comb, a projection providing a shoulder against which the hook-shaped lever bears to prevent separation of the combs, said 75

lever being pivotable to a position which removes its hooked portion from said shoulder and permits separation of the combs.

3. Narrowing mechanism for flat knitting machines comprising at each side of the fabric an inner and outer comb of narrowing points, means for locking together the combs at each side whereby they will have conjoint motion, said means including a lever having a pivotal connection with one of the combs, and having a portion for engaging with a part of the other comb to prevent separation of the combs, and means including a cam member supported on the machine at a point along the path of travel of the combs, and a member carried by one of the combs to engage with said cam member as the combs move inwardly of the fabric, and

thereby pivot said lever to a position which will permit separation of the combs.

4. Narrowing mechanism for flat knitting machines comprising at each side of the fabric an inner and an outer comb of narrowing points, one of said combs having a projection providing a shoulder, a lever having a pivotal connection to the other comb, and having a hooked portion to bear against said shoulder to thereby prevent separation of the combs, a cam member supported on the machine at a point along the path of travel of the combs, and said lever including an extension which engages with said cam member as the combs move inwardly of the fabric, and pivots the lever to a position which permits separation of the combs.

KENNETH HOWIE.
